tion of New Jersey.

Application April 21, 1939, Serial No. 269,095

15 Claims. (Cl. 49—84)

My invention relates to the manufacture of ampoules.

The main purpose of my invention is to manufacture ampoules from bottle stock as distinguished from making them from tubing stock, using the bottoms of the bottles as the bottoms of the ampoules and thus requiring change in one end only of each.

A further purpose is to cheapen the manufacture of large ampoules.

A further purpose is to draw the top of hot bottle stock into a stem to form an ampoule, performing the operation while the bottle stock is still hot from blowing and adding heat as may be desired or needed to maintain the part drawn at a suitable temperature or to heat it to a desirable higher temperature than that to which it may have cooled, or to vary the point at which the drawing takes place by distribution of the drawing over the length of the shoulder and/or neck.

A further purpose is to provide bottle stock and to stretch the necks and permissibly the shoulders of the bottles into tapered stems at the ends of which the ampoules are ultimately to be filled and by the breaking of which the ampoules are made available for withdrawal of content.

A further purpose is to permit ampoules of large capacity to be made shorter and of larger diameter than at present permissible, since the drawing or stretching will take place from the neck diameter and not from the body diameter. The ampoule thus has a larger base, lower center of gravity and shorter stem, all combining with the better base to produce a more stable as well as a stronger ampoule.

A further purpose is to permit the same choice in ampoules of composition, quality and character of glass and variety in the shape and distribution of the thickness of the glass, particularly shoulders and necks—which are to be stretched into stems—that is now exercised in the production of bottles.

A further purpose is to thicken the walls of ampoule stems and shorten them as compared with the existing art by reducing the initial diameters of the walls from which they are drawn as compared with the diameters of the bodies of the ampoules.

A further purpose is to control the ultimate thickness of the walls of the reduced ends of ampoules by control of the thicknesses of the bottle necks from which the ampoules are constructed.

A further purpose is to thicken the stem of an ampoule at a constriction for breaking uses.

A further purpose is to form double-stemmed ampoules by forming necks—one closed—at both ends of a blown bottle and drawing out both necks.

A further purpose is to facilitate manufacture of ampoules of irregular shape.

A further purpose is to form the outer edges 10 of the shoulders of ampoules and/or the shoulders with a glass thickness comparable with that of corresponding bottles, permissibly equal to or greater than the glass of the ampoule bodies.

A further purpose is to provide for marking 15 and decoration as well as strengthening of particular parts of ampoules by initially blowing these parts within molds, permitting names, figures, and other decoration as well as strengthening thicknesses to be applied during the blowing operation, as in the case of bottles.

The invention relates to the methods involved.

As at present generally constructed, ampoules are made from glass tubing by stretching the tubing to produce tapered stems with or without 25 tool-formed spear heads. The stems may be formed at both ends or at one end only. In the latter event the tubing is closed to form a bottom at the other end of each. Whether or not the ends of the reduced stems are to be constricted 30 to form spear heads makes no difference from the standpoint of the invention.

As the size of the ampoules increases the commercial desirability of manufacturing from tubing is affected by increase in the cost of the 35 tubing, which increase is out of all proportion to the increase in the size of the tube used.

For manufacture of small ampoules glass tubing forms an excellent base or stock, both because of its regularity, which is important in 40 ampoules of very small diameter, and because of the cheapness of small tubing. However, even in this case the formation of flat bottoms from the tubing is apt to introduce considerable irregularity in the bottoms of the ampoules.

It is apparent that the stretching or drawing 45 out of a tube reduces its thickness and that if the operation be a purely lengthening operation this reduction in thickness begins at the point where the full diameter of the tube is first reduced. Consequently the thickness of the stem will be reduced as compared with the thickness of the tube wall.

In addition to the thinning where the tube is reduced from full tube diameter the necessity 50 for drawing the tube always involves extra gas

use and with large tubes involves also difficulty and care in the drawing operation which would not be necessary if the initial diameter be reduced.

The present invention contemplates stretching the open ends of blown containers, herein generally referred to as bottles, to form tapered stems terminating in points, the ampoules thus produced being made up in part of the blown bottle "stock" and in part of stretched stems. The invention offers the greatest benefit in ampoules of medium and large sizes. It offers advantages also in strength and adaptability to varied needs and desires in use.

The blown bottle "stock" may be of existing bottle types, whether hand-blown or machine blown, selected as appropriate for the drawing or stretching operation in order ultimately to produce the ampoules of the invention, in which case the method of manufacture need not go back of the selection and use of existing types of bottles for the stock. On the other hand the stock may be blown bottles of special size, thickness, distribution of glass, size or thickness of neck or shoulder, composition or other characteristic suited to the construction of the ampoules, in which case the method of manufacture of such ampoules may start with the blowing of the bottles.

The capability of increasing the diameter of the body for a given capacity of ampoule while maintaining any predetermined size of neck and hence convenient length of stem permits shortening both the body and the stem of the ampoule and broadening its base. It will thus change from an ampoule that must be laid on its side or supported in a receptacle to a shorter one of larger diameter which rests upon the bottom as does a bottle and which is stable against upsetting.

Because I start with blown stock I am able to take advantage of all means available in the bottle art which will be of advantage in the completed ampoules, including permissible strengthening of the outer rim or shoulder of the bottle and elsewhere, marking the volume or instructions, or decoration, etc., in the glass; and I am able to select my diameter of body without having to watch the considerable increase of cost which increase of diameter would require in the case of a tube.

I have preferred to illustrate the invention by a few simple forms and with but two machines by which the methods can be carried out.

Figure 1 is a longitudinal section and partial elevation of a bottle which has just been blown in a mold, and before finishing the neck.

Figure 2 is an elevation of the same bottle after the neck flange has been formed showing also structure by which it can be hand stretched.

Figure 3 is an elevation of the bottle of Figure 2 after the neck and part of the shoulder have been stretched.

Figure 4 is an elevation of the structure of Figure 3 after it has been tooled to form a spear head.

Figure 5 is an elevation of an ampoule of the general type of Figure 4 showing a fuller stem.

Figure 6 is an elevation partly sectioned showing a bottle having thickened shoulders and neck.

Figure 7 is an elevation to slightly enlarged scale, partly sectioned, of a bottle having a neck of hour-glass type.

Figure 8 is an elevation, partly sectioned, showing the neck as converging.

Figure 9 is an elevation partly sectioned of a bottle of special shape having necks at both ends, one of them closed.

Figure 10 is a front elevation partly sectioned of a bottle intended for a special form of stoppered seal.

Figures 11 and 12 are an end elevation and a side elevation partly sectioned, respectively, of a machine for stretching the necks and shoulders of bottles to form ampoules.

Figure 13 is a fragmentary section on line 13-13 of Figure 12.

Figure 14 is a side elevation, partly sectioned, showing other mechanism for the same purpose.

In the drawings similar numerals indicate like parts.

The contour, particularly the longitudinal cross-section of the shoulder and drawn reduced end (stem) of an ampoule affords opportunity for wide variation due to the different thicknesses of the glass and different neck diameters and shoulders.

In the practice of the broader invention I soften the necks and permissibly also the shoulders of the bottles to a point where they can be drawn. In order to conserve heat as much as possible I take the bottles directly after they have been blown, i. e., as soon as the bottles have solidified and can be handled.

Where it is desired that thick spear heads shall be formed and the stems are to be thickened at the spear heads I provide extra glass for this thickening either by initial thickening of the necks or shoulders from which these parts of the stems are formed, or I soften a larger area in order from it to provide the additional thickness before tooling.

The character of the stems produced will depend upon many factors including the diameters of the necks and shoulders before stretching, the thicknesses and kinds of glass and the lengths of the sections made plastic and stretched.

The lengths, diameters and strengths of the stems are capable of control by manipulating the factors above, using larger neck diameters or areas made plastic, for example, for large and long stems than for small and short stems. The stems may range from capillary forms, such as in Figure 4, to much fuller and thicker stems, of which one is seen in Figure 5.

In Figure 1 is shown an existing type of bottle 15 used as stock. It is within a mold 16, just having been separated from a punty rod. Its neck has not been finished. As seen in Figure 2 the bottle comprises outer body walls 17, bottom 18, shoulder 19, neck 20 and neck flange 21.

For convenience in reference the shoulder and neck are referred to together as comprising the top of the body and as hereinafter more clearly pointed out the operations described may be performed upon the shoulder or the neck, or portions of either or both of them, additional heat being applied as needed either to take the place of heat being dissipated or to control the point at which drawing wholly or chiefly takes place during any part of the drawing operation by controlling the relative plasticity of this part as compared with the rest of the top of the body.

It will be obvious that the stretching of the neck and permissibly also the stretching of a portion of the shoulder can be effected by hand after the glass shall have been softened over the area to be stretched. For the purpose of

handling the hot bottle in Figure 2 I show a holder 22 and a hand stretching tool 23. The selective application of heat is indicated by gas nozzle 24. An air blast cooling means, to control stretching at individual points and to cool the stem is shown at 25.

It is not necessary of course that the neck flanges of the bottles intended to be stretched should be finished to the same shape or in the same manner as if the bottles were intended to be complete for use as finished; merely that there be provision for engagement of the neck by a tool of some kind used in the stretching.

In Figure 3 one form of ampoule is shown having a stem 26 which has been stretched from the neck and from the inner part of the shoulder at 27 so that the contour blends nicely with the outer (larger) portion 28 of the shoulder. The stem is then cut at some such point as 29 by any suitable means such as a gas flame or by a rotating disc 30. Both of these are common in the art.

The form left by the cutting comprises a completed ampoule unless it be desired to make special provision for breaking in which case the stem is tooled at 31 (Figure 4) to form a spear head form which is still regarded as a stem.

The ampoule is supplied to the trade with its end 32 open. Subsequently this end is sealed in any appropriate manner.

In Figure 5 a very much larger and fuller stem is shown, the ampoule of the figure having stem 26' and tooled (spear head) breaking contraction 31'. The forms of Figures 4 and 5 are not intended to show limits, but are merely illustrations to give some idea that a variety of product is available, for which my invention is suited and for which it offers considerable advantage.

The thickness of tubing used and present in the existing methods of manufacture of the larger sizes of ampoules is sufficient to stand drawing out into stems, but the cost of larger tubing is a part only of the larger cost of such ampoules when made from large tubing as compared with the cost of producing them from bottles.

Not only does the reduction in the diameter of the tubing to form the ends of the tubing into stems require a considerable amount of time on account of the extent of reduction necessary, but there is a corresponding additional heat cost to soften the larger diameter and to maintain the end of the tubing soft during the operations of drawing out and tooling.

With the present invention the drawing or stretching operation can begin with any diameter desired, as this means merely the manufacture of the bottle with a neck of the diameter needed. Where thickness of stem walls is an object the neck can be made correspondingly thick.

Whether the neck alone be intended to be drawn out or the neck and shoulder be intended both to be stretched, is a matter in large measure of choice of the manufacturer to secure just the contour desired and to control the length and diameter of the stem.

I recognize that the contour of the section drawn may be controlled not only by selection of the area heated, or additionally heated to control the parts from which the stem is drawn, and the extent of softening but by selectively cooling portions of the area drawn, in the event that a portion of the area is drawing more rapidly than is desired. For this reason I indicate the cooling nozzle at 25.

Figure 6 is inserted for the purpose of teach-

ing a rather obvious fact that the exterior of the bottle stock may be reinforced in any way desired as by rings or bands 34 and 35.

The shoulder and neck may be given extra thickness as at 36 and 37. The indication of content and decoration can be "blown in the glass" as in the case of bottles.

In Figure 7 an hour-glass neck 38 is shown with a very small opening. If the outer part only, 39, be softened a long fine stem will be secured, the outer flare of the neck having to be overcome by stretching before the diameter of the stem interior begins to become smaller than that of the initial throat 40. Tapering in the opposite direction, as at 41 (Figure 8) increases the contraction and shortens the stem.

Where stems are to be provided at both ends of the ampoule (Figure 9) my invention is applicable by blowing necks at both ends 20' and 20", the one neck being closed as at 42 in order to permit blowing. Each of these necks is provided with a neck flange 21 and the two ends can be stretched coincidentally or separately after softening in the manner indicated herein.

In the form shown in Figure 10 a stoppered ampoule is shown having a permissibly tooled tapered opening 43 for a stopper 44. The neck 45 is flared beyond the stopper at 46 and is provided with a flange 21'.

It is the intention here, as in my other forms, preferably to start with the bottle hot as it comes from the mold, but the fact that the bottle has cooled does not here, nor in my other forms prevent use of my invention. It merely means that if it has been cooled with or without annealing, stretching of the neck or neck and shoulder, here extension 46, requires careful preliminary heating and subsequent annealing. Whatever the fact as to this the extension is softened at an area enough larger in diameter than the stopper so that the stopper seat will not be affected and the drawn glass will not encroach upon the space for stopper insertion. The softened area is then stretched by pulling on the neck flange to provide a glass tube 47 which is desirably nearly straight and larger in diameter than the stopper and which is integral with the neck of the bottle ampoule. It will be evident that the normal contraction due to stretching may be offset by the amount of flare, so as to produce an ultimate tube of the type desired. The flange will be cut off, as in the other forms.

Ampoules of the general character of that shown in Figure 10 now exist but are made by heat-sealing tubes in tapered openings, the difference between this ampoule of the prior art and mine being that the tube beyond the stopper seat is drawn in my case and is part of the blown glass. My ampoule is filled under vacuum conditions, filled and the end of the tube is heat-sealed in the same manner as in the case of the existing stoppered ampoules having the terminal tubes heat-sealed in the tapered openings.

The machine-blown or hand-blown bottles intended for stretching can be transferred by hand as they are taken hot from the molds to any suitable stretching mechanism.

Though as indicated the ampoules can be drawn out by hand it is easier to secure regularity of form by drawing them out by machinery. For this reason mechanism for the purpose has been described, the mechanism being in part hand operated.

Because the bottle may be rotated or the flame may be revolved, alternatively as desired, the

structure has been shown for both types of operation.

In Figures 11, 12 and 13 mechanism is shown which is intended to rotate the bottle and the neck flange independently and at the same rate. The frame 48 rests upon a suitable base and supports a bearing 49 by bracket 50 and also supports bearing 51. The bearing 49 carries a shaft 52 and a bevel gear 53. Gear 53 is rotated by a mating bevel gear 54 upon shaft 55 which rests in bearing 51.

The shaft 55 carries a pulley 56, keyed to the shaft and driven by a suitable belt. It also carries a sliding clutch member 57 splined to the shaft and cooperating with a clutch member 58 which freely rotates upon the shaft when the clutch is disconnected. Clutch 58 is rigid with pulley 59 whose crossed belt 60 in turn drives a pulley 61 upon a shaft 62. The sliding clutch 57 is thrown by a lever 63 pivoted at 64 and yoked at 65 to engage pins upon clutch member 57.

The shaft 62 is mounted from the base 66 in bearings 67 and 68 and carries a bevel gear 69 meshing with a bevel gear 70 upon a shaft 71. The shaft 71 has bearing in the base and drives a plate 72 upon which is mounted a suitable chuck 73 holding successively bottles 74.

The bottles are inserted in the chuck by hand so that the bottle neck flanges may be engaged by cooperating jaws 75 and 76 having pivotal connection at 77. They are capable of being opened by wedge action between their lever ends 78 and 79. The pivot 77 is carried by a frame 80 surrounding and driven by shaft 62. The height of the frame is controlled by lever 81.

Lever 81 is fulcrumed at 82. The lever 81 straddles a vertically movable sleeve 83 which has trunnions 84 at opposite sides of the sleeve fitting within recesses in the straddling lever, so that lifting and lowering of the lever, acting through these trunnions, lifts and lowers the non-rotatable sleeve 83.

The sleeve 83 surrounds the frame and, in vertical position, lies between collars 85 and 86 which are fastened to and rotate with the frame 80. Lifting and lowering end 87 of the lever 81 therefore lifts and lowers the frame 80 and with it the jaws 75 and 76.

The construction is such that the shaft rotates and in rotation carries the frame with it, but the frame, though carried rotarily by the shaft, can move up and down upon the shaft.

The two collars are rigid with the frame and hence both rotate and lift with it.

Between the two collars lies the nonrotatable sleeve, surrounding the frame and, by engagement with the collars, lifting the frame and lowering it or permitting it to lower.

The sleeve is lifted and lowered by lever 81 through the trunnions on the sleeve.

The rotatable frame 80 lifts and lowers upon the shaft 52 at the same time that the shaft and frame are controlled to rotate together by pin 88, which passes through the shaft and rides in slots 89 in opposite sides of the frame.

Because the shaft 52 is lifted and lowered by the lever 81, the movement of the frame and of the frame-carried clutch lever members permits release of these lever members at the upper end of the stroke of the frame, the release being effected by engagement of the upper arms 78 and 79 of the clutch members with the tapered lower end 90 of the shaft 52. Engagement with the neck flange in the lowered position of the parts is effected by gravity by forming guiding

5 slopes 91 upon the lower ends of the clutch members 75 and 76, the weight of the parts drawing them together about the neck of the bottle after they have slipped over the neck flange.

Heating of the neck or neck and shoulder of the bottle is effected by gas supply nozzle 92 and areas which stretch too much, relatively to other areas can be controlled by moderate cooling through the use of air blast nozzle 93.

The operation of the device is as follows:

A hot bottle is placed in chuck 73 and the frame is lowered by means of lever 81 until the under tapered surfaces of lower clutch ends 75 and 76 separate by engagement with the neck flange and close again below it. The bottle, which retains as much heat as practicable from the blowing operation is then heated by blast from supply 92 along the area which is intended to be stretched until it is plastic, the parts meantime being rotated by gears 53, 54 and 69, 70. The connections are such that the chuck and clutch members rotate at the same speed.

When the bottle neck is sufficiently softened for the drawing operation the lever 81 is lifted and the neck is drawn. During or after the drawing operation the flame through gas pipe 92 is reduced or cut off; and air is applied through pipe 93 if it be desired to chill portions of the area which is being drawn so as to slow the drawing operation at these portions on each, or, after the operation, to cool the glass as quickly as may be safe so that the ampoule may be removed. At the upper limit of lifting of the frame by lever 81 the lower wedge end 90 of shaft 52 separates the lever ends 75 and 76.

In the construction of Figure 14 the frame 94 mounts guides 95 and 96 in which hollow shaft 97 is movable vertically between limits set by a collar 98 secured to the shaft at the top and the walls of a slot 99, which walls slide over pin 100. The pin 100 holds in place an interior rod 101 at whose lower end is located a clutch-releasing tapered nose 90. This nose operates upon the same kind of a clutch and in the same manner at the upper end of the hollow shaft movement as in the case of Figures 11, 12, and 13. Clutch members 102 and 103 are pivoted at 104 and present upper ends 105 and 106 for release of the clutch when at the upper ends of their movement they engage nose 90.

The shaft is lifted and lowered by lever 107 pivoted at 108 and connected with the hollow shaft at 109.

The disc 110 is supported about the shaft by a bracket 111. It does not rotate. A circular groove 112 in the lower face of this disc is supplied with gas through a pipe 113.

A generally corresponding disc 114 is grooved at 115 in its upper face to correspond with the groove in the lower face of the non-rotatable disc 110. A gasket 116 seals between the edges of the grooves, and the faces of the two discs may additionally seal one against the other. The two grooves together thus form a continuous gas supply for revolving gas pipes 117 terminating in nozzles 118, connecting with groove 115 in the lower rotating disc. The arrangement is effective to heat the section of the bottle which is to be made plastic. The area heated and made plastic may be varied, as by bending the pipes 117 or by variation in the height of the bottle. In the form of Figures 11, 12 and 13, of course, the height of the flame and its angle of im-

pingement can be varied by hand before or/and during the stretching operation.

The disc 114 carries an upwardly extended sleeve 119 which surrounds the hollow shaft and has bearing against it near opposite ends, in whatever vertical position the hollow pipe assumes. The sleeve is supported by the disc 110 through a bearing comprising cones 120 and 121 located upon the disc and upon the sleeve respectively, and balls between. The height is adjusted by the position of threaded cone 121 and is locked by threading a nut upon the sleeve. No separate nut is shown as a pulley 123 serves this purpose.

The pulley 123 is located at the upper end of the sleeve. It is driven by belt 124. The height of the bottle may be adjusted by the use of different heights of chucks or holders 73 as is true also in the form of Figures 11, 12 and 13, simplifying the construction. This is preferred for the reason that it is then not necessary to use any of the common means of adjustment by raising the height of the table.

In view of my invention and disclosure variations and modifications to meet individual whim or particular need will doubtless become evident to others skilled in the art, to obtain all or part of the benefits of my invention without copying the structure shown, and I, therefore, claim all such in so far as they fall within the reasonable spirit and scope of my invention.

Having thus described my invention what I claim as new and desire to secure by Letters Patent is:

1. In the art of manufacture of glass ampoules, the method which comprises molding a body in the shape of a bottle having a bottom and an open neck from a mass of molten glass by a blowing operation and within a mold, reheating the neck and stretching said reheated neck to form an elongated ampoule stem open at its end.

2. In the art of manufacture of glass ampoules, the method which comprises molding a body in the shape of a bottle having a bottom, a shoulder and an open neck from a mass of molten glass by a blowing operation and within a mold, reheating the shoulder and neck and stretching said reheated shoulder and neck to form an elongated ampoule stem open at its end.

3. In the art of manufacture of glass ampoules, the method which comprises molding a body in the shape of a bottle having a bottom, a shoulder and a neck from a mass of molten glass by a blowing operation, the neck being of greater thickness than that of the remainder of the body, reheating the neck and stretching the reheated neck to form an elongated ampoule stem open at its end.

4. In the art of manufacture of glass ampoules, the method which comprises molding a body in the shape of a bottle having a bottom and an open neck from a mass of molten glass by a blowing operation and within a mold, reheating and stretching the neck and determining the length of the stem and the strength of the stem 60 of the completed ampoule by the diameter of the neck.

5. In the art of manufacture of glass ampoules, the method which comprises molding a body of glass having a central portion, one closed end 70 and an open neck at the other end, from a mass of molten glass, said closed end and open neck being smaller in cross section than said central portion, by a blowing operation and within a mold, reheating both the closed end and the neck 75

and stretching both said reheated end and reheated neck to form elongated ampoule stems, one open at its end.

6. In the art of manufacture of glass ampoules, the method which comprises molding a body in the shape of a bottle having a bottom and an open neck from a mass of molten glass by a blowing operation and within a mold, allowing the bottle to cool, preheating the bottle, additionally heating the neck and stretching said additionally heated neck to form an elongated ampoule stem open at its end.

7. In the art of manufacture of glass ampoules, the method which comprises molding a body in the shape of a bottle having a bottom and an open neck from a mass of molten glass by a blowing operation, allowing the shape blown to solidify and, before it cools appreciably, adding heat to the neck and stretching said reheated neck to form an elongated ampoule stem open at its end.

8. In the art of manufacture of glass ampoules, the method which comprises molding a body in the shape of a bottle having a bottom and an open neck from a mass of molten glass by a blowing operation and stretching the neck to form a stem while the neck is still hot and before the blown shape has been annealed, adding needed heat as required to maintain the neck in condition for stretching.

9. The method of forming a glass ampoule having a stoppered closure and a tube of larger diameter extending beyond the stopper which comprises molding a body in the shape of a bottle having a bottom and a neck internally flared from a diameter suitable for the stopper to a diameter larger than the largest diameter of the stopper to form a stopper seat by a blowing operation from a mass of molten glass, reheating the portion only of the flared neck lying beyond the position of the stopper seat and stretching the reheated portion of the flared end of the neck progressively to contract said portion of the neck into approximately a cylindrical shape.

10. The method of forming a glass ampoule having a stoppered closure and a tube of larger diameter extending beyond the stopper which comprises molding a body in the shape of a bottle having a bottom and a neck internally flared from a diameter suitable for the stopper to a diameter larger than the largest diameter of the stopper to form a stopper seat, by a blowing operation from a mass of molten glass, tooling the part of the neck intended to receive the stopper to form a stopper seat, reheating the portion only of the flared neck lying beyond the position of the stopper seat and stretching the reheated portion of the flared end of the neck progressively to contract said portion of the neck into approximately a cylindrical shape.

11. A glass ampoule comprising a body, bottom and top molded from molten glass by a blowing operation and within a mold and a stem formed by subsequently stretching the top.

12. An ampoule comprising a container of bottle type having side walls, bottom, shoulder and neck blown within a mold from molten glass and a terminal stem subsequently stretched from the neck and from part of the shoulder.

13. An ampoule having a body of uniform diameter, a bottom, a shoulder free from stretching at the junction with the body and a neck, all molded from molten glass by a blowing operation and within a mold, the neck being stretched subsequently to form a drawn stem.

14. A glass ampoule having a body, bottom, shoulder and flared neck blown within a mold from molten glass by a continuous blowing operation, a stopper for the neck and a cylindrical tube drawn from the same glass as the neck, integral with the neck and larger in diameter than the stopper.

15. A glass ampoule having a body, bottom,

shoulder and neck adapted to receive a stopper, molded from molten glass by a blowing operation and within a mold, a stopper for the neck and a drawn tube continuous with the neck, 5 larger than the stopper and extending about and beyond the stopper.

FRANK H. WHEATON, JR.
